CLAIM

The ornamental design for a posterior condyle cutting block, as shown and described.

DESCRIPTION

FIG. 1 is a front perspective view of a posterior condyle cutting block, showing our new design;

FIG. 2 is a front elevation view of the posterior condyle cutting block of FIG. 1;

FIG. 3 is a rear elevation view of the posterior condyle cutting block of FIG. 1;

FIG. 4 is a first side elevation view of the posterior condyle cutting block of FIG. 1;

FIG. 5 is a second side elevation view of the posterior condyle cutting block of FIG. 1;

FIG. 6 is a top plan view of the posterior condyle cutting block of FIG. 1; and,

FIG. 7 is a bottom plan view of the posterior condyle cutting block of FIG. 1.

The broken lines in the drawings are for the purpose of illustrating portions of the posterior condyle cutting block that form no part of the claimed design.
